UNITED STATES PATENT OFFICE.

GEZA HORVATH, OF DETROIT, MICHIGAN.

EXPANSIBLE INTERNAL-SMOOTHING TOOL.

Application filed November 23, 1922. Serial No. 602,715.

To all whom it may concern:

Be it known that I, GEZA HORVATH, a citizen of the United States of America, residing at Detroit, in the country of Wayne and State of Michigan, have invented certain new and useful improvements in Expansible Internal-Smoothing Tools, of which the following is a specification, reference being had therein to the accompanying drawings.

10 This invention relates to an expansible internal smoother, and has special reference to that class of tools having retractible or foldable smoothing jaws which permit of the tool being inserted through a small opening or passage to operate upon a surface of greater diameter or area than the walls of the opening or passage through which the tool is inserted. This type of tool can be advantageously used in the can making industry for smoothing or subjecting the inner wall of a can or part thereof to internal pressure, the tool being entered through the neck of the can to operate upon the inner wall of the body of the can.

20 25 My invention aims to provide an expansible internal tool wherein the shiftable parts of the tool are constructively arranged to be well braced and reinforced for a smoothing operation, at the same time supported so that smoothing jaws may be retracted and folded. The construction entering into the tool is exceedingly simple, durable and easy to maintain in an operable condition, and this construction will be hereinafter specifically described and then claimed.

30 Reference will now be had to the drawings, wherein Figure 1 is a plan of the smoothing tool;

35 Fig. 2 a cross sectional view taken on the line II—II of Fig. 1;

40 Fig. 3 is a perspective view of the detached head plate;

Fig. 4 is a longitudinal sectional view of the smoothing tool;

45 Fig. 5 is an end view of the same;

Fig. 6 is a perspective view of a detached slideable jaw supporting member, and

Fig. 7 is a perspective view of the detached jaw body.

50 In the drawings the reference numeral 1 denotes a tubular tool body having its outer end provided with a plurality of equally spaced parallel longitudinally disposed arms 2 which have the outer ends thereof connected by a cylindrical head 3 provided with diverging or radially disposed slide-ways 4.

55

Slidable in the slide-ways 4 of the head 3 are retractible jaw supporting members 5 having the inner ends thereof beveled, as at 6 to be engaged by the wedging facets 7 of the reciprocable plunger 8 slideable in a bushing 9 in the tool body 1 and adapted to have power applied to its inner end so that the outer end of said plunger may be forcibly interposed between the beveled inner ends of the members 5 to distend said members in a radial direction relative to the axis of the tool.

The retractible members 5 are retained within the slide-ways 4 of the head 3 by a head plate 10 having a central opening 11 providing clearance for the end of the plunger 8. The head plate 10 also has radial slots 12 housing coiled expansive springs 13 which have the inner convolutions thereof encircling studs 14 on outwardly extending brackets 15 carried by the retractible members 5, said brackets being slideable in the slots 12. The outer convolutions of the springs 13 encircle studs 16 carried by the head plate 10 and cooperating with the studs 14 in preventing displacement of the springs 13. The expansive force of these springs is adapted to hold the members 5 normally retracted in engagement with the facets 7 of the plunger 8.

The head plate 10 is positioned relative to the head 3 by dowel pins 16' and secured to said head by a plurality of screws 17 extending through bosses or barrels 18 of the head 3 into the head plate. The head plate 10 has peripheral flanges 19 seated on the end of the head 3 with said flanges spaced apart, as at 20 to provide clearance for the retractible members 5.

95 Pivottally mounted in the retractible members 5 by transverse pins 21 are the inner ends 22 of swingable jaws 22, said jaws being disposed to abut the head 3 and seat on the periphery thereof when said jaws are in an active or laterally extending position, as best shown in Fig. 4.

100 Pivottally connected to the jaws 22, intermediate the ends thereof, by transverse pins 24 are the forked or bifurcated ends 25 of links 26, said links having the inner ends thereof pivottally mounted, by transverse pins 27, between apertured ears or lugs 28 carried by a reciprocable sleeve-like member 29 slideable on the tool body 1. This reciprocable sleeve-like member is adapted to have power applied to its inner end to swing

the jaws 23 from the active position shown by full lines in Fig. 4 to a folded or inactive position as shown by dotted lines in the same figure. The forked or bifurcated ends 25 of the links 26 provide clearance for the outer ends of said jaws which are adapted to swing inwardly between the arms 2 of the tool body 1, and to provide clearance for portions of the jaws 23 the plunger 8 has its walls recessed or cut away, as at 30.

Mounted in the outer ends of the jaws 23 are pins or stub shafts 31 on which are journaled smoothing rollers or rolls 32, arranged so that the axes of said smoothing rollers are parallel to the axis of the tool body when the smoothing jaws are in active positions. The smoothing rollers are also disposed so that the ends thereof will be in a plane with the head plate 10 and free to engage angular walls should occasion require. For instance at the juncture of a can bottom or can breast with a can body.

With the jaws 23 retracted and folded the tool body 1 can enter a can body through 25 the neck thereof and this may be accomplished while the tool body is being rotated. After the tool body has been lowered to a desired position within the can body, the reciprocal member 29 can be actuated to 30 unfold or distend the smoothing jaws, and then the reciprocal plunger 8 may be actuated to simultaneously shift the jaws 23 outwardly and cause the rollers 32 thereof to exert an internal pressure against the walls 35 of the can or other structure. Shifting the jaws 23 outwardly causes the springs 13 to be placed under additional tension, and when the plunger 8 is retracted the expansive force of the springs 13 causes the jaws 40 to be simultaneously retracted and retained against the facets 7 of the plunger 8. With the jaws 23 retracted the reciprocal member 29 can be actuated to fold the jaws inwardly into substantial parallelism with 45 the tool body, at which time the tool body may be removed from the can in which it has been operating.

It is thought that the utility of my invention will be apparent without further description, and while in the drawings there is illustrated a preferred embodiment of my invention, it is to be understood that the construction is susceptible to such changes as are permissible by the appended claims.

55 What I claim is:—

1. An expandible internal smoothing tool comprising a tool body having a head, radially disposed members slidable in the head of said body, foldable and retractible smoothing jaws pivotally supported by said

slidable members, means reciprocable on said tool body adapted for folding and unfolding said smoothing jaws, and means in said tool body adapted for distending said smoothing jaws.

65 2. An expandible internal smoothing tool as called for in claim 1, wherein said reciprocable folding and unfolding means includes a sleeve on said body and links pivotally connected to said sleeve and to said smoothing jaws.

70 3. An expandible internal smoothing tool comprising a tool body, foldable and retractible smoothing jaws at the outer end of said tool body, means reciprocable on said tool body adapted for folding and unfolding said smoothing jaws, and means in said tool body adapted for distending said smoothing jaws, said distending means including a wedging plunger axially of said tool body and having a wedging action to 75 simultaneously distend said jaws.

80 4. An expandible smoothing tool comprising a tool body having arms supporting a head, retractible members slidable in said head, smoothing jaws pivotally supported by said retractible members and adapted to swing between the arms of said tool body, and means on said tool body adapted for swinging said smoothing jaws to and from 85 said arms.

90 5. An expandible smoothing tool as called for in claim 4, and means in the head of said tool body adapted for retracting said retractible members.

95 6. An expandible smoothing tool as called for in claim 4, and means axially of said tool body adapted for distending said retractible members.

100 7. An expandible internal smoothing tool comprising a tool body smoothing jaws having inner ends pivotally supported at the outer end of said tool body and adapted to be swung into substantial parallelism with said body, means on said tool body to facilitate swinging said smoothing jaws, and means in said tool body adapted for simultaneously distending said smoothing jaws when said jaws are laterally disposed relative to said tool body.

105 8. An expandible smoothing tool as called for in claim 4, and rollers carried by the outer ends of said smoothing jaws.

110 In testimony whereof I affix my signature in presence of two witnesses.

GEZA HORVATH.
